UNITED STATES PATENT OFFICE.

JAMES O. MEREDITH AND GROVER MEREDITH, OF MARION, INDIANA.

ANCHORING DEVICE.

Application filed December 3, 1926. Serial No. 152,458.

This invention relates to an anchoring device, and particularly to a construction adapted to be supported by a concrete or similar base.

5 In prior constructions of this character no provision has been made for adjusting the clamping jaws to engage materially different widths of beams or rail bases so that separate devices were necessary to effect a proper clamping action when the base of the member to be clamped was of greater width than that for which the pivotal mounting of the jaws was designed. Further, the means 10 for effecting a simultaneous movement of the jaws has generally comprised a separate element which in the case of a wedge was liable to be displaced in use or lost when removed to release the clamping jaws.

We overcome such objections by the provision of a unitary structure having a support for the member to be anchored and means by which the jaws may be adjusted toward and from each other to accommodate materially different widths of the base of 25 said member with which the jaws cooperate in their clamping action. We also provide clamping means mounted upon one jaw and acting upon a lever from the opposite jaw by which a simultaneous rotative clamping 30 action of the jaws is effected, such means being disposed at opposite sides of the supported member and readily accessible for tightening or adjusting the clamping jaws which frequently becomes necessary when such member is subjected to vibration as in 35 the case of a rail fastener.

The invention has for an object to provide a novel and improved construction including a support for the member to be anchored, 40 with opposite jaws engaging the base of said member, and means for adjusting the fulcrums of said jaws toward and from each other and effecting a simultaneous clamping action thereof.

45 Another object of the invention is to provide a new construction of clamping jaws having overlapping lever ends with a threaded lug upon each jaw adjacent its axis of rotation adapted to carry a clamping device mounted to engage the lever from the opposite jaw.

A further object of the invention is to provide an improved form of support for the anchoring device comprising a casing having a toothed under face disposed to co- 50 operate with a clamping jaw having a

toothed pivot adjustably engaging said face and a free lever end for cooperative action with a clamping device.

The invention also has for an object to 60 provide a novel construction of casing for cooperation with the anchoring device and comprising complementary members having inwardly projecting flanges adapted to form a bearing for clamping jaws and exterior 65 ribs disposed to prevent movement of the casing within the concrete or other material in which it is embedded to form a firm support.

Other and further objects and advantages 70 of the invention will be hereinafter set forth and the novel features thereof defined by the appended claims.

In the accompanying drawing:

Figure 1 is a longitudinal section on the 75 line 1—1 of Figure 2;

Figure 2 is a top plan;

Figure 3 is a section on the line 3—3 of 80 Figure 2;

Figure 4 is a plan of one of the jaws; and

Figure 5 is a side elevation of the opposite 85 jaw.

Like numerals designate corresponding parts throughout the several figures of the drawing.

The invention is designed for application to bars or beams in building construction for the purpose of anchoring the same to a proper base and also for application as a rail fastener, while if reversed in position 90 may be used as a hanger for suspending a beam or rail member.

In the form of the invention shown the box or casing 10 is preferably elongated and provided with transverse ribs 11 adapted to be seated in the concrete or similar base in which the casing is embedded. This casing comprises opposite members joined at a central line and each provided with an inwardly extending flange 12 having upon its under face teeth or similar projections 13 adapted to form a support for the adjustable mounting of the clamping jaws to be hereinafter described. These flanges extend longitudinally of the casing and the toothed portions 100 13 are of such extent as to provide for an adjustment for materially different widths of the base 14 of the beam or rail 15 to be supported and anchored in position.

The jaws 16 are formed with a hook portion at their engaging ends and with a pivot or fulcrum 17 provided with teeth or pro-

jections 18 adapted to be engaged with the teeth 13 to permit an adjustable mounting of the jaws relative to each other for rotative movement in their clamping action. Extending from the fulcrum 17 of each jaw is a lever end 19 disposed in a substantially horizontal plane and extending beyond the pivot of the opposite jaw where it is provided with a bearing portion 20. Each of the jaws is formed adjacent its fulcrum with a threaded lug 21 within which a clamping screw 22 is mounted and bears at its free end against the portion 20 at the free end of the opposite lever. The action of this screw, as shown in Figure 1, is to force downwardly the end of the lever 19 of one jaw and raise the lug 21 of the opposite jaw, producing a simultaneous clamping movement of the two jaws. This movement is equalized and the jaws effectually locked in position by the location of the clamping devices 22 at each side of the jaws where they are readily accessible for operation if it be desired to release the jaws or to take up any slack due to wear or vibration.

As shown in Figure 4 the toothed faces 18 of each jaw are disposed at opposite sides thereof to engage the adjusting faces of the spaced flanges of the casing while the lever portion 19 is offset from the center of the jaw in order to cooperate with a similar portion from the opposite jaw which permits close nesting of the levers and the location of the bearing portions in alignment with the lugs.

It will also be noted from Figure 3 that the casing is formed of increasing width downwardly so that when embedded in proper material it is firmly held against withdrawal while the ribs thereon prevent any longitudinal displacement. The aperture at the face of the casing is formed of such area as to protect the clamping levers while the inward flanges at the face thereof prevent side movement of the jaws when in clamping relation.

From the foregoing description the operation of the invention will be apparent and it will be seen that a unitary structure is provided in which there is a cooperative action between the casing and the clamping jaws while the latter are adapted for a wide field of adjustment to engage objects of different widths without affecting their joint pivotal action when engaged with such objects. The rail rests upon the support and the anchoring jaws are engaged therewith and with the under surface of the support so that the pressure transmitted by adjustment of one jaw upon the other produces an inward movement thereof to effect the clamping action. The arrangement of the extended levers from the jaws in connection with the clamping devices provides for the maximum leverage and for firmly retaining

the jaws in engagement. The structure of the casing provides a firm anchorage or support for the member resting thereon and a fixed pivot with which the fulcrum of the jaws may cooperate in their clamping action. 70

While the specific construction of the casing and clamping jaws have been shown and described, the invention is not confined thereto as changes and alterations may be made without departing from the spirit of the invention as defined by the appended claims. 75

Having thus described our invention, what we claim as new and desire to secure by Letters Patent of the United States is:—

1. In an anchoring device, a support, opposite clamping jaws fulcrumed thereon, and means for adjusting the fulcrums of said jaws toward and from each other to provide different areas of clamping action. 80

2. In an anchoring device, a support, opposite clamping jaws fulcrumed thereon, means for adjusting the fulcrums of said jaws toward and from each other to provide different areas of clamping action, and a clamping device mounted upon one jaw to engage a lever extended from an opposite jaw. 90

3. In an anchoring device, a support, a pivoted jaw having a fulcrum adapted to be adjusted upon said support and an extended lever end, and a clamping member mounted to engage said lever end. 95

4. In an anchoring device, a support, a pivoted jaw having a fulcrum adapted to be adjusted upon said support and an extended lever end, and a clamping screw mounted upon an opposite jaw member and adapted to engage said lever end. 100

5. In an anchoring device, a support, opposite clamping members having overlapping lever ends, a threaded lug on each jaw adjacent its axis of rotation, and a clamping device mounted in said lug to engage the lever from the opposite jaw. 105

6. In an anchoring device, a casing provided with supporting flanges to receive a member to be anchored, opposite clamping jaws having their fulcrums engaging one of said flanges respectively and adapted to be adjusted toward and from each other, and means for simultaneously actuating said jaws. 110

7. In an anchoring device, a casing provided with parallel flanges adapted to support a member to be anchored and provided upon their under face with toothed surfaces, opposite clamping jaws disposed between said flanges and having toothed surfaces adjacent their fulcrums and means for adjusting said clamping jaws. 115

8. In an anchoring device, a casing provided with parallel flanges adapted to support a member to be anchored and provided upon their under faces with toothed surfaces, opposite clamping jaws disposed between 120

130

5 said flanges and having toothed surfaces adjacent their fulcrums, a horizontally disposed overlapping lever extended from each fulcrum, and a lug carrying a clamping device adjacent the fulcrum of each jaw and bearing upon the free end of the lever from the opposite jaw.

10 9. A jaw member for an anchoring device having at opposite sides of the jaw toothed bearing faces, a lug extended from said jaw, and a lever offset from the center of the jaw and extended laterally therefrom.

15 10. In an anchoring device, a casing having its body increasing downwardly in width and provided with transverse retaining ribs, inwardly projecting flanges at one face of said casing forming a support, and spaced clamping means disposed to engage an object resting upon said flanges.

20 11. In an anchoring device, a casing com-

prising complementary members having at their meeting edges inwardly projecting flanges toothed upon their under faces, spaced clamping jaws having an adjustable bearing upon said toothed faces and disposed intermediate of said flanges, and means for simultaneously actuating said jaws.

12. In an anchoring device, a fixed casing having a support for a member to be anchored, and opposite clamping jaws having fulcrums adjustable upon said support toward and from each other to provide for clamping engagement with portions of members of materially different width.

In testimony whereof we affix our signatures.

JAMES O. MEREDITH.
